FACE GRINDING

Harry P. Troendly, Chicago, Ill., and Frank Bares,
Waterbury, Conn., assignors to The Torrington
Manufacturing Co., Torrington, Conn., a cor-
poration of Connecticut

Application November 14, 1942, Serial No. 465,824

19 Claims. (Cl. 51—118)

This invention relates to improvements in face grinding, and more particularly to improved methods of and means for grinding planar face or end portions of coil springs, bushings, rings, pins, short shaft elements, and similar units. The method and equipment herein described have been particularly, although not exclusively, designed for grinding the opposite end faces of coil compression springs, hence in the interest of brevity, the description will make reference, without limitation, to its principles and usage in this connection.

The more prevalent practices prior to commercial usage of the present improvements in the grinding of coil springs, involved the use of one or more grinding discs or wheels operating adjacent to one or both of the ends of the several work units. Heretofore prevalently the units in process were passed but once, or at most a very limited number of times through the grinding zone, with no established uniformity of movement of the different work units with respect to abrasive material, and under conditions such that an excessive feeding pressure was set up between each grinding disc and the adjacent faces of the units in work. This older practice presents a number of serious and expensive disadvantages, among which may be noted an irregular or uneven removal of metal from the two ends and unevenness in each face of the springs, resulting in failure satisfactorily to approach a true planar aspect, where desired, of the end face or faces of the work piece. A further and economically very serious disadvantage of the noted older practice, is found in the gouging effects of the relatively sharp ends of springs or the like, particularly upon their first encounter with the abrasive face of the grinding disc, thus seriously channeling the face of the wheel, and resulting in need for frequent dressing of the wheel, and its early replacement.

Other disadvantages of heretofore prevailing face-grinding practice have been noted in the markedly differential abrasive treatment, in semi-automatic or automatic grinders, of different units of work of the same batch or lot. This disadvantage has been particularly prevalent in those types of grinding equipment wherein the work units are carried into and across the grinding field by a reciprocal work carrier having a rectilinear movement, and coacting with a rotating grinder wheel. It is inevitable in equipment of this type that some of the units of work, such as springs, are subjected to a longer period of abrasive action than others in the same lot, and

further that some of the units are ground by portions of the grinding disc which operate at a lower linear speed than abrasive portions acting on other of the elements, thus resulting in markedly differential removal of metal from the face portions under treatment.

Another of the older types of grinding equipment employs a rotating work carrier of a relatively small diameter in conjunction with a rotatable grinding disc, but with the two rotatable elements in such relation that different units of the same batch of work pieces receive markedly different abrasive treatment. It is accordingly a general object of the present invention to overcome each and all of the difficulties above noted, and to provide for a more uniform grinding effect, particularly in face grinding operations, than has heretofore been provided in machines of the type under discussion.

20 A further and very important object of the invention is attained in a face grinding assembly utilizing rotatable abrasive discs or wheels in which, for reasons to be discussed, the abrasive discs are self dressing when used with metals of the usual ranges of hardness, including coil springs formed of steel wire.

Yet another important object of the invention is attained in an improved correlation of operating and control characteristics of an automatic grinding assembly. The operational result of these improvements is reflected in a more uniform and more gradual feeding rate and feeding pressure maintained through the greater portion of the grinding period between the abrasive discs and the work units in process; an improved relation of the paths of movement of the work holding portion of a work carrier wheel and the grinding discs, and an improved relation between rotative speeds and hence of linear speeds of different portions of the work holding element and the grinding discs.

Still another object of the invention is attained through a relatively slow yet substantially uniform infeed rate and pressure, together with a fairly rapid rotative speed of work holder, resulting in what may be termed a "light touch" treatment of the springs or other work units in traversing the grinding zone.

50 A further object of the invention is attained in improved facilities for a substantially continuous, yet technically intermittent operation of the grinding assembly, attained through an improved relation of a plurality of work holding wheels operable alternately in conjunction with the grinding discs constituting a grinding field

alternately functioning on the work in the plurality of work holders. This enables loading or unloading a given one of a plurality of the work holders while another thereof is in operative position with the work units therein in the grinding zone.

An additional and practically important objective of the present assembly is attained in an improved stop shifting arrangement for quickly preselecting a desired one of several fixed lengths of infeed travel. This facility, as will later be apparent, enables alternate grinding operations on work units of differing length, without time-consuming changeovers in machine setting.

Yet another and important object of the invention is attained in a markedly superior infeed mechanism which is of somewhat broader application than to the present field of face grinding, and which serves to effect an extremely low rate of approaching movement, of work and a power tool, and similarly is adapted for maintaining an exceedingly light yet uniform feeding pressure between the work piece and tool.

Numerous additional objectives of the invention, to note only a few of the more outstanding, include novel and improved facilities for effecting a slow infeed motion to bring work and grinder elements toward each other, and as desired, to effect a quick translatory separation of the work and tool such as a grinder disc; an improved power assembly for tilting a rotatable work holder between a loading and unloading position and a position for advance of the work holders into the processing zone; improved means for effecting a translatory movement of a work holder such as a rotatable Ferris wheel into and out of the grinding field; improved means for quickly shifting, when desired, a grinding head to and from the grinding zone whereby to enable quick access to any portion of the work when desired, or quick access to any one or a plurality of coacting grinding wheels as for service attention or replacement.

Yet another object of the invention is attained in an improved device herein exemplified as a rotatable work carrier or Ferris wheel, in which the work units are floatingly retained, each in an individual compartment or pocket, and in which the compartment is so proportioned to the work unit that the latter is free to be shifted endwise or to rotate in either direction when in the grinding zone.

The foregoing and numerous additional objects will become more fully apparent when considered in connection with the accompanying description taken in conjunction with the drawings illustrating a single preferred embodiment of the invention, and in which:

Fig. 1 is a top or plan view of a grinder assembly including a pair of normally spaced, mutually opposed grinding discs, and a pair of rotatable Ferris wheels constituting carriers for the units of work in process;

Fig. 2 is a side elevation partly in section of the assembly shown by Fig. 1, but illustrating one of the Ferris wheels in operative position to subject the springs or work units therein, to abrasive action in the grinding zone, and showing an opposite Ferris wheel in a position for loading or unloading of its work units;

Fig. 3 is a vertical sectional elevation in a plane indicated by line 3-3 of Fig. 1, and particularly illustrating the more important elements of the infeed mechanism;

Fig. 4 is an end view of one of the grinding heads, carriages therefor and certain of the in-

feeding elements all as viewed along line 4-4 of Fig. 1;

Fig. 5 is a side elevation of one of the Ferris wheel assemblies, this view showing some of the Ferris wheel structure as same would appear when viewed from line 5-5 of Fig. 1;

Fig. 6 is a sectional elevation showing certain elements of the Ferris wheel drive and tilting mechanism, as same would appear when viewed from line 6-6 of Fig. 1;

Fig. 7 is a diagrammatic, single-line showing, illustrating the relation of paths of movement of the work carrying band of the Ferris wheel, and one of the grinding wheels or discs, and

Fig. 8 is a schematic hydraulic diagram embodying an outline of the various hydraulic units of the assembly, the preferred circuit, and locations therein of the several hydraulic controls.

Referring now by characters of reference to the drawing; for definiteness of alignment, as well as certainty of leveling and sufficiency of support, the assembly is preferably mounted in part on a base structure conveniently formed of structural steel shapes, and indicated generally at 20. The longitudinal elements shown are cross-tied at substantial intervals as by spacer or distance elements 21. Although the sill elements may be continuous from end to end, the structure may in fact consist, as shown, of similar base units on opposite sides or ends of the grinder assembly proper, and the latter supported on a separate intermediate base 23 as will appear. The upper portions of elements 20, indicated at 24, may be utilized as spaced, paired track elements; on the track portions 24 are a plurality of the work holder or Ferris wheel assemblies, each comprising drive mechanism, and tilting mechanism, for the related wheel, the whole of which is mounted on a deck generally indicated at 25. As will appear from a comparison of the two Ferris wheel assemblies shown by Figs. 1 and 2, each of the decks 25 together with the elements thereon, is adapted for a translatory movement, by means hereinafter described, to enable shifting of the Ferris wheel assembly, or each thereof into and out of the grinding zone. Details of structure of each of the Ferris wheel assemblies will be hereinafter more fully described.

In the embodiment selected for present disclosure, the grinding assembly consists of a pair of axially displaceable grinding head assemblies, generally designated at 26 in Fig. 1, the two heads being mounted in relatively opposed relation as will appear from Figs. 1 and 3. Since the two assemblies 26 are or may be identical in structure, it is sufficient to note that each is comprised of major elements including a grinder wheel 30, drive motor 31, and suitable power transmission means generally indicated at 32, for driving the grinder wheel shaft 33 from the motor 31. The rotatable elements of the grinder head are supported by and form parts of an upper base structure 34, which is movable for alignment purposes upon an intermediate slide base or carriage generally indicated at 35 the latter in turn being slidably supported on a main slide base structure or carriage 36. A suitable infeed mechanism later to be described in detail, serves to advance both of the grinding heads generally indicated at 26, in an axial direction, toward or away from each other whereby to establish the infeeding motion and pressure set up for grinding purposes between the abrasive discs 30 and the work units in the grinding zone or field indicated at 39.

It will now have appeared by way of general

preliminary description of physical assembly that the Ferris wheel assemblies are adapted, after loading, to be moved to bring their work-carrying portions into the field between the wheels 30, but that the Ferris wheels are to be moved into such zone one at a time. The purpose of the plurality of Ferris wheels will now have become obvious in that one of the wheels may be brought to a substantially horizontal position as appears at the left hand side of Fig. 2, in which position the wheel is best adapted to be loaded with or relieved of the work units in process. This may be done obviously while the Ferris wheel at the right hand side (Fig. 2) of the grinder assembly, is being rotated to bring the work units carried thereby in successively traversing relation to the grinding zone, wherein the units are acted upon by the opposed spaced abrasive wheels or discs 30. In this manner the grinder heads may be kept substantially continuously in operation, although it will be noted that the abrasive discs thus operate on successive batches of the units in work alternately presented by the opposite Ferris wheels.

It is perhaps in order first to describe the details of structure of the grinding heads and in-feeding mechanism. For conformance with machines now in production usage, reference will be made to an assembly employing the described pair of opposed grinder heads, although it will be understood that, provided only a suitable abutment is afforded for one end of the springs or like units in process, a single grinder head and appurtenances may of itself embody the principles of the present invention. Similarly, instead of employing a pair or more of the Ferris wheel assemblies such as supported by decks 25, only a single such rotatable work holder may be utilized in full practice of the more essential steps of the method and features of structure.

Grinding assembly and infeed mechanism

The grinding assembly proper includes as a primary supporting structure, the hollow base 23, heretofore generally mentioned. This may consist of a heavy walled structure of a generally rectangular shaping in plan, and suitably reinforced by internally projecting, integral ribs or the like 37. The upper longitudinal margins of base 23 are machined to provide smooth track elements which serve slidably to receive similarly machined surfaces on the lower margins of each of the pair of hollow, generally rectangularly shaped, main slide bases or carriages 36. Supported on and slidably movable relative to each of the main slide bases 36, is an intermediate slide base or carriage 35, heretofore noted, the structures 35 and 36 meeting along horizontal planar surfaces 41, those on base 36 constituting trackage for the companion surfaces on the slide base 35. From this it will now appear that the structures 35 and 36 may be and normally are movable together as a unit axially of the grinder and of the fixed base 23. However for purposes of certain adjustments, and sometimes for quick translatory movements at the end of the grinding period, and for occasional access to the grinder discs 30, the intermediate slide bases 35 may each be moved along and upon the associated bases 36.

Rotation of each of the grinder discs 30 is effected through a driving motor 31, provided with a multiple V-belt drive pulley 42 and a multiple groove, variable speed driven pulley 43, pulleys 42 and 43 being connected by any desirable plurality of V-belts 44. Obviously, any suitable

form of power transmission may be employed between the motor 31 or other suitable prime mover, and shaft 33 for the grinding disc 30. The abrasive discs 30 each consists of a hollow center, or annular type abrasive wheel, the center opening of each of which is normally closed as by a circular closure plate, (shown diagrammatically in Fig. 7), and for which a suitable adjustment (not shown) may be provided for retraction of the closure plate to keep it in or slightly to the rear of the plane of the grinding face of the wheel. Many expedients for this purpose are well known in the art, and need not here be detailed. It is a distinct preference in connection with the present method of grinding that the center portion of the wheel 30 be entirely devoid of any abrasive action on the springs or other units of work in process, and that this hollow center area and its closure, be a substantial portion of a total diameter of the wheel. For example, in an abrasive disc of 48" diameter, a relieved or hollow central area, and hence the closure therefor, should be at least of the order of 16" diameter.

With further reference to the abrasive disc assembly it is preferred, for obvious reasons, laterally and peripherally to enclose the abrasive discs 30, as by partly cylindrical, side open shielding elements 45, each of which may be connected to an exhaust duct system to assure removal of flying particles of abrasive material from the wheels and fine particles resulting from grinding the work in process. For purposes of augmenting circulation in and beyond the enclosures 45, and with some incidental cooling effect, the wheel plate 46, constituting the backing element of the wheel, is provided with a plurality of radial vanes or fins 47 (Figs. 2 and 4).

Referring now further to the details of the main and intermediate slide bases of each of the grinding head assemblies, there may be provided between the slide bases 35 and 36, separate adjustable track elements 50 and 51, best appearing in Fig. 4, and provided with takeup provisions to compensate for occasional wear, as indicated by studs or screws 52 and 53. It is a preference in providing for the slidable association of main slide base 36 on base 23, to include trackage elements 55 on base 23 and a coaxing and slidably engaging element 56, making contact with the undercut face portion of each of elements 55. Take-up for wear is conveniently provided for by set screws 57 and 58 (Fig. 4).

A further advantageous feature of the grinder assembly is found in the provision for effecting, when desired, a relatively quick axial shifting movement of the intermediate slide base. This is desirable as will appear, when changing certain of the variable length of work stops, and possibly at other times for affording quick access to the grinding wheels 30. This arrangement consists of a pair of hydraulic cylinders on each side of the slide base assembly, and indicated generally at 60. These are supplied with fluid, preferably oil, kept under pressure as through feed and return pipes 61-62 constituting part of a hydraulic system hereinafter described. When it is desired to effect a quick translatory movement of the intermediate carriage, a control valve is actuated causing relative displacement of the cylinder and piston, (outlined in the diagram of Fig. 8), within each of the cylinders 60. The cylinders of these assemblies may be connected to wing brackets 63 (Fig. 4), the latter being fixedly carried by the base 23, whereby a relative longitudinal movement of the intermediate slide base is

effected as desired and for the purposes noted, by admitting oil under pressure to corresponding ends of the cylinders, and proportionately relieving the opposite ends of the several cylinders.

Proceeding now to a description of the infeeding mechanism, the immediate source of infeed motion comprises an elongate hydraulic cylinder 64 preferably several feet in length, the disclosed example illustrating a cylinder containing a piston (outlined in Fig. 8), adapted for a 48" stroke. The cylinder 64 is supplied from the hydraulic system through a special feed valve hereinafter referred to in connection with the hydraulic supply system. The cylinder 64 is further of a nature to be supplied from either of its ends, and with an outlet at the other end, so that the two ports 65 and 66 may each alternately serve as an inlet and as a discharge port, as will hereinafter better appear in later reference to the hydraulic system. The piston in the cylinder 64 is of so-called double-face type, and is direct-connected to a piston rod 70, extending through a suitable stuffing box or gland. The rod 70 is secured as by a threaded end and double nut arrangement 71-72 to an apertured upstanding arm 73 on an elongate cam bar generally indicated at 74. This camming element is carefully machined to provide a gradually sloping wedge profile, resulting in a camming surface 75, and the cam bar is guidedly constrained to a rectilinear path of movement through provision of guiding or track elements 76. A follower coacting with the attenuated, gradually sloping surface 75 of cam bar 74, consists of a double-arm link 69 between the spaced arms of which is pivotally carried a follower roller 80, the follower assembly including link 69, being constrained to follow a vertical path of movement, (normally downwardly for infeeding motion of the grinder heads) as by spaced, opposed guide members 81, serving as a type of crosshead. The follower structure is provided at the end opposite roller 80, with a pivot pin 82. As thus far described, the elements of the infeeding mechanism are or may be common to the opposed, oppositely movable, grinder heads for infeeding thereof. It will be significantly noted that the follower structure 69 and pivot 82 operate in a plane produced downwardly of that which extends medially of the grinding field 39.

It will also have appeared that as the piston rod 70 is actuated say to the right (Fig. 3) the effect of the gradually sloping camming face 75, operating on roller 80, hence on the link 69, will be to move the latter downwardly very slowly and in a vertical plane. This motion is carried on to the grinder heads in the example shown through the provision of a pair of bellcrank levers. Since each of these levers is individual to one of the grinder heads, it is regarded as sufficient to describe only one thereof. The noted bellcrank lever for the left hand assembly (Fig. 3) consists of a long arm 83 provided with a shear pin or bolt 79, and arranged for normal pivotal movement about a short shaft 84, the latter being fixedly supported in suitable bearing arms (not shown) in base 23. The shorter arm of the bellcrank lever is indicated at 85 and there are, by preference, a pair of these spaced apart in parallel relation, the companion short lever arms engaging laterally extending trunnions 86 carried by a two-part, substantial collar structure 90. The latter is axially fixed in position between a pair of projections on a sleeve structure 91 from which it will appear that incident to normal infeeding motion derived from piston rod 70, the

arm elements 85 and both of the carriage or slide base structures 35 and 36 will have an extremely slow, yet highly uniform infeeding movement, such as slowly and regularly to advance the grinding head at the left of the assembly (Fig. 3) toward and into the grinding zone 39. To complete the connection between lever arms 85 and the slide base structures, it will be noted that main slide base 36 is provided with a depending projection 92 horizontally apertured at 93 for the reception of an operating bar 94. The latter is fixedly held against axial movement and in its horizontal position by a pair of lock nuts 95 and 96, the latter serving as a stop element to determine the infeed movement, as will later appear. The operating bar 94 is provided at its outer end with a head element 97 and is provided with a bushing 100 within the sleeve 91, this sleeve and the bar 94 being normally kept in operative assembly through a feed-disengaging nut 101 which is internally threaded to engage external threads on the outer margin of sleeve 91. It now becomes apparent that by removing the feed disengaging nut 101, the carriage or slide base 36 may be 20 operatively disengaged from the operating bar and hence from the infeeding mechanism associated with the bellcrank lever structure 83-85. This is desirable at times, for example, in backing away the slide bases and grinder thereon for the purpose of renewing worn grinding wheels or for other service attention. It is preferred that the bushing 100 be of bronze or the like, to avoid any tendency for the adjacent steel elements 91 and 94 to seize, and resist their operative disengagement.

The function of the shear bolt 79, above referred to, will now be obvious from its location and the earlier reference thereto. In the event of abnormal resistance to infeeding movement of the grinder assembly and slide base, occurring from any cause, this element serves to prevent breakage by yielding or shearing, thus permitting continued downward movement of arm 83 about a separate pivot 102, thus obviating any continuing movement, perhaps disastrously, of the short arm 85 of the bellcrank lever, and hence of the slide base assembly and grinding elements.

For limiting the infeeding movement of each slide base 36 and parts thereon, there is provided a hollow operating bar 94, through which extends the rotatable shaft 103, common to both grinder heads where more than one is employed. At each outer end of shaft 103 is a hand wheel 104, and disposed approximately below the respective wheels 30 is an assembly including a pair of headed stop elements 105 and 106. One or more stationary brackets 107 conveniently being extended portions of base 23, serve to receive a sleeve element 108, mounted therein for a limited longitudinal slidable movement, and being slidably keyed to the bracket 107. In each end of the sleeve 108 is a tapped bore portion, one such portion being provided with right hand threads and the other with left hand threads, respectively engaged by external threads on the stop elements 105 and 106. It will be noted that the latter are bored and key slotted so as slidably to receive the shaft 103. Thus by rotating either hand wheel 104, shaft 103 will rotate the stop elements 105 and 106 and, through the keyed connection therebetween, the floating stop elements will be moved axially along shaft 103. It is to be noted that the pitch of threads coacting with the stop elements 105 and 106 is identical, although

the direction of threading is reversed on either with respect to the other, because of which the end faces or heads of stop elements 105 and 106 may be adjusted to any predetermined distance apart in which adjustment they will remain until subsequent rotation of adjusting shaft 103.

As heretofore mentioned, during the grinding operation with infeeding movement, the stop elements 96 heretofore mentioned move toward the heads of elements 105 and 106, and when abutting contact is made, the movement of each element 96 ceases and hence the heads or face portions thereof, of elements 105 and 106 are always at a predetermined spacing, and the amount of infeed movement of stops 96 and hence the grinding heads, is assured to be uniform for each grinding operation. Thus, neglecting abrasive wear for which separate adjustment is made, successive batches of units in work will, when desired, be finished to exactly the same length.

It should be noted as a preference that sleeve 108 is made slidable to compensate for usual tolerances in manufacture of elements 69, 83, 85, etc., and for the purpose of attaining a positive clamping of both grinding heads at the end of their infeed movement. For example, it is sometimes possible, because of tolerance differences in the parts of the two infeeding assemblies of the respective grinding heads, that, but for the floating stop assembly, infeed movement of one head might be determined by abutment of associated parts 96 and 105, slightly before determination of infeed by corresponding parts of the opposite assembly. Such a result would cause uneven strains in the levers and other infeed elements of the respective grinding head and carriage assemblies, and furthermore, might at times leave the paired grinding assemblies without assurance that they would stop infeeding in the same place in succeeding grinding operations.

The difficulty stated is overcome by making the sleeve 108 slidable, within moderate limits, in the bracket 107. In this manner whichever pair of coacting abutments are first engaged, such initial engagement is enabled to cause a slight axial movement of the entire stop assembly 105, 108 and 106, toward the other movable stop 96. It will now be apparent that both grinding heads will have their infeeding movement determined at the same time, and that in succeeding operations, both grinding heads will cease their approaching movement at an even distance apart.

It may be noted in respect to the positive clamping effect above referred to, that to obtain accuracy in finished length of the ground units in work, all slack, play or looseness is desirably removed from the infeeding mechanism at the end of infeed movement of the heads and slide bases. The stops 105 and 106 are so adjusted that at the time their abutment faces are contacted by the elements 96, the cam 74 is still permitted to move an inch or so to the right (Fig. 3). This slight period of end movement serves to relieve the infeed mechanism of all play, and effectively clamps the grinding heads in their now fixed inner positions, through the stop mechanism described. This result is possible largely because of the "floating" characteristic of the sleeve 108, because of which the floating stop assembly (hereinafter referred to by reference to floating stops 105 and 106), is enabled to serve as a distance piece tightly bridging and spacing the two heads a fixed axial distance apart.

One of the advantages afforded by the present assembly is that of facilitating alternate grind-

ing operations on batches of work pieces of differing lengths. In order to enable a quick changeover from work pieces of a given length in one of the Ferris wheels, to those of a greater or lesser length in the other Ferris wheel, means are provided for quickly changing the length-of-work stops incident to the requirement for different initial axial placements of the grinder wheels due to longer or shorter work pieces. To this end the main slide base 36 is provided in its outer wall portion with a large rotatable nut 110. The element 110 is carried by and rotatable (but not axially movable) in a hand wheel screw 111. The nut 110 acts essentially as a turret member, and serves threaded to receive a pair or more of adjustable stop screws shown at 112 and 113. It will be noted that each of these stop elements is individually adjustable endwise, upon predetermined rotation, in the element 110, the latter being in non-threaded but rotatable relation to the hand wheel screw 111 while the latter is externally threaded and engages internal threads in a bore 114 in the end wall of, or a fitting in, main slide base 36. The intermediate slide base 35 is provided with a depending abutment or projection 115 of such length that it can be engaged by only one at a time, of the stop screws 112-113. A suitable handled element (not shown) is provided for effecting a quick rotary shift of the turret nut 110 for changing from one of the stops to the other, according to the length of work to be initially disposed in the grinding zone 39. Locking means (not shown) are provided for fixing the adjusted position of nut 110, and locking provisions are also preferably employed (but omitted for clarity of illustration), to prevent casual or unintended displacement of member 111.

For the purpose of enabling freedom of movement of the nut 110 between different stop positions, it is desirable, during such adjustment, to shift the slide base 35 axially out of a position of abutment by either of the stop screws last noted. This is accomplished through the agency of the paired, hydraulic cylinders 60 heretofore referred to. In order to assure that the translatory movement of slide base 35 is never such as to bring the grinding wheels 30 into mutual engagement, there is provided an upstanding internal projection 116 on the base 36, this projection serving to receive a safety stop screw 117 which is initially adjusted to such position that it is engaged by projection 115 of base 35 at one extreme of movement of the base 35 relative to base 36, thus preventing any possibility of impact of the two wheels or of impact of either wheel with the work carrier in case the latter happens to be in place in the grinding zone.

It is thought that, following the description of the various stop provisions made both for purposes of determining the range of infeed movement and providing facilities for shifting between work units of different lengths, the purposes of the cylinders 60 will have become apparent. Each of these assemblies 60 is of double end type, and each is provided with the described pair of fluid connections to its opposite ends, such as 61 and 62. The pistons (shown in outline in Fig. 8) in the assemblies 60, are of double face type and may be directly connected to piston rods 122 and 123 (Fig. 1); these latter are or may be rigidly connected each to a somewhat L-shaped bracket 124 or 125, these brackets being directly connected to the intermediate slide base or carriage of the associated grinder head assembly. It may be noted that the hydraulic cylinder assemblies 60,

connected into the hydraulic system as suggested by Fig. 8, serve a number of purposes. Among these they act under certain conditions to return or back feed the grinder heads after or as the infeed operating cylinder assembly 64 has moved the cam follower assembly 80-69 to a relatively retracted or initial position as shown, for example, by Fig. 3. The paired cylinder assemblies 60 serve also the function of cushioning the infeed movement, and of providing a relatively elastic infeed drive for the grinder, the hydraulic system and particularly the control valve (hereinafter described) for the cylinders 60, being such as to permit a very slight piston displacement in each cylinder 60 to attain this result. As heretofore implied, the cylinders 60, when energized to move their pistons in one direction, serve to move the slide base 35 away from the length-of-work stops 112-113.

Several minor refinements may be noted as facilitating initial adjustment as well as service attention to the assembly. Among these may be mentioned the provision of a vertical centering dowel 130, the lower end of which is centrally or medially socketed in slide base or carriage 35 and the upper end of which is similarly socketed in the base of the housing structure 131 in which are provided the bearings for shaft 33 carrying wheel 30. At each side of the structure 131 is provided a shifting lug assembly, the lug of which is indicated at 132, capable of adjusting the structure 131 to the right or left, through a screw 133. Through the provision of the dowel 130 and the lugs 132, each grinder wheel 30 may be adjusted so as to bring its planar grinding face in truly parallel relation to the median plane through the grinding field, or somewhat differently stated, to maintain the face of each grinder wheel parallel to the face of the companion wheel and with each face in a plane truly normal to the line of infeed movement. It will further have appeared that the dowel 130 constitutes a positive driving connection between housing 131 and the intermediate slide base 35.

As an expedient for maintaining an optimum tension of belts 44, each motor 31 is provided with a separate base 134. This is hingedly secured as at 129, to the housing structure 131. The opposite side, being that visible in Fig. 3, is provided with a turnbuckle adjustment 135, the upper element of which is pivotally connected to base 134 and the lower end of which is pivotally connected to a hinge structure formed in part on a lower flange of the housing 131. Thus extension of the turnbuckle 135 serves slightly to rock the motor and base 134 about the hinge pivots, whereby selectively to tension the several V-belts 44.

A further refinement is to be noted in the provision of an adjustable stop, consisting of an upstanding apertured lug 136 on cam bar 74. The lug 136 is provided with an adjusting screw 137. This stop may at times be desirable in case a full stroke of the cam bar is not needed or not desired for a predetermined infeed movement. It is entirely possible and contemplated that the adjustable stop 136-137 may be pivotally mounted to be swung out of stop position in case its function is not necessary, and yet may be returned to operative position when wanted, and adjusted as desired.

The operation of the grinding assembly and infeeding provisions therefor has been referred to in part by earlier references to functions of the several elements of this assembly. To summarize this phase of operation, it may be noted that the

grinder discs 30 are first placed in a retracted axial position so as to provide a width of grinding field 39 appropriate to receive therebetween, the loaded Ferris wheel containing work units such as springs, which are of known approximate initial lengths. In keeping with the described stop-screw provisions for quick change to accommodate different work-piece lengths, the turret nut 110 is rotated to bring into operative position the selected one of the stop screws 112 or 113, the one selected cooperating with the depending arm or lug 115 on the intermediate slide base. Thus is determined one axial limit of movement of the slidable supporting structure for the grinding head. In case any adjustment is necessary by reason of normal wear of the abrasive disc 30, this wear may be compensated for by rotation of the threaded element 111, provided with a hand wheel as shown. Assuming the finished or ground length of springs to have been determined, rotation of hand wheel 104 serves to bring the floating stops 105 and 106 either closer together or farther apart, in the former case to provide for shorter finished length of work pieces, and the latter to provide for relatively longer finished lengths, as of the springs to be ground.

For rotation of the grinder disc 30 as by motor 31, the latter in a production construction is of 30 H. P., 1200 R. P. M. rating, and with a normal (although moderately variable) drive ratio between motor 31 and shaft 33 such that the grinder discs rotate at a speed of the order of 440-530 R. P. M. The paired opposed grinder heads are or may be identical hence the foregoing description of setting and operation of each, will suffice for both.

Assuming now that one of the Ferris wheels is in place and rotating to bring the work pieces into, through and beyond the grinding field, the fluid in the hydraulic system, such as oil under pressure, is admitted to the connection 65 at the left hand end (Fig. 3) of cylinder 64, and permitted to be discharged from the right hand end as from connection 66. This, as will later appear, for infeed movement, is a so-called trickle feed, so that there results a very slow movement of the piston in cylinder 64. This results in a barely perceptible infeed-producing movement of piston rod 70, and therewith, the cam 74, and results from the action of the cam face 75 on roller 80 and follower 69. The result is an extremely slow, uniform, downward motion of the follower and hence of the outer ends of the paired bellcrank lever arms 83. There results a still slower but nonetheless even infeed movement of the short arms 85 of the bellcrank levers, producing through elements described, the equally slow yet regular motion, impelling the paired abrasive discs 30 toward each other and against the faces of the work pieces being ground.

By reason of the improved infeed mechanism there results also a substantially uniform infeeding pressure between the discs or each thereof and the faces of the work units, as will now appear obvious. The infeed motion described continues until abutment of the floating stops 105 or 106 respectively by the abutment nut 96 on each of the grinding head structures, being then mechanically determined. However, in case the work units are compression springs, the end faces of which are in process of being ground, the loading of the springs will result in some continuation of pressure between their end faces and the discs 30, which pressure persists through a so-called sparking-out period. This

remnant loading of the springs and the extent of their compression depend upon the characteristics and specification of the springs, and are taken into account in reference to finished ground length at the time of setting the stops 105—106 as by one of the hand wheels 104.

It is important, incident to the method hereinafter to be more fully described, to maintain no more than a light touch grinding contact between the springs and abrasive discs. As a convenient means of determining the nature and extent of grinding contact between the work and the discs, each of the motors 31 is provided, in its supply line, with an ammeter or other means providing an instant indication of motor loading. The operator is thus enabled to tell instantly whether the rate of infeeding motion is excessive or insufficient, and through control of the rate of admission of fluid under pressure to cylinder 64, may maintain his ammeter readings at optimum values. It may be noted that upon completion of the grinding cycle, return of the grinder heads including the wheels 30 to a separated position ready to receive the next work batch is accomplished by the reverse motion of the inclined plane of assembly identified with cam 74, follower 80, hydraulic cylinder 64, etc., the return motion of the grinder assembly working also under the action of the hydraulic cylinders 60 and associated elements. The arrangement and structure of the valves in the hydraulic system are such that rate and direction of fluid flow into and out of cylinders 60 and 64, provide where desired, a relatively quick return action of the grinder heads.

Rotatable work holders and associated driving, tilting and shifting mechanism therefor

Reference has heretofore been made, solely by way of general structure, to the provision of rotatable work holders sometimes referred to as Ferris wheels, as the agencies for carrying a great number of the units in work, into the grinding field 39, thence through and out of such field. The improved method of grinding effected by the present structure contemplates the use of a Ferris wheel of a much larger diameter than that of either of the abrasive discs 30. The grinding method resulting from the particular relation of Ferris wheel work band, and disc area and relative position of the grinding wheels thereto, will be hereinafter discussed more fully in detail, but it may be noted that, for example, in case the abrasive discs are of the order of 48" diameter, the work-carrying band portion of the Ferris wheel should be of the order of 84" as its maximum diameter.

The general structural arrangement of each of the Ferris wheels as such, is best seen in Figs. 1 and 2, wherein the wheel proper is indicated generally at 140. This wheel is conveniently of spoke and hub construction, in which the spokes are shown at 141 integral with or secured to a hub structure 142, and the wheel proper rotatively supported through its hub portion on a shaft 143 (Figs. 5 and 6). The work carrying band of wheel 140 is in the nature of an annular compartmented structure, confined say to the outer rim portion, and being in an 84" wheel, say of 12" to 14" width, this band portion being pointed out generally by numeral 144. This work band is built up of a substantial number, say several hundred metal bushings in the nature of short cylindrical elements 145. These are suitably secured in place as by welding together, with or

without any desired further banding or assembly structure, none being shown in detail. The bushing elements 145 are each preferably so dimensioned and proportioned to the usual sizes of the work pieces to be ground, that the latter units are floatingly received therein, free to rotate each on its own axis, and each in its individual pocket or compartment constituted by one of the elements 145. It now appears obvious that the bushings 145 are necessarily somewhat shorter than the finished length of work units, so that the opposite end of each such unit may project appreciably beyond the bushing, even when ground to finished length. Each of the Ferris wheels 140, supported through its shaft 143, is mounted together with a driving unit for rotation of the wheel, in a frame structure identified with major elements 146, 147, 148.

Normal rotation of the Ferris wheel is most desirable with usual classes of work in process, such as springs, at a rate of the order of 2 to 3 R. P. M. This rotation is accomplished by a small motor indicated generally at 150 (Figs. 5 and 6) which is or may be direct-connected to a reduction gear unit 151, provided with a power takeoff pinion shown at 152, and the latter meshing with a gear 153 directly secured to shaft 143. It now becomes obvious that operation of motor 150, through the reduction unit 151 and gears 152—153 will effect the desired rotation of Ferris wheel 140. To facilitate manual loading and unloading of the work units to be ground, into and from the band 144 of bushing-receptacles 145, it is highly desirable to provide for tilting 35 actuation of the Ferris wheel, preferably between a horizontal position as shown at the left hand side of Fig. 2, and a vertical position as shown at the right hand side of the same figure. When located horizontally, the wheel is at a convenient 40 height for easy access by the operator to the open-end, pocket-forming bushings 145. Since the springs or other work pieces are introduced vertically and downwardly into the pockets therefor, it is desirable to provide temporary closures 45 for at least one side face of the work band of the wheel. This is cared for by the requisite number of arcuate-shaped closures 154 associated with a frame structure of the wheel by means (not shown) which enables the closures 154 to be 50 brought under the wheel portions loaded with the work units. Some of the closures are desirably fixed in position, while others are made detachable. It will appear as obvious that when the Ferris wheel is moved to bring a portion of 55 its periphery into the grinding field, such portion is left uncovered for free access to both faces of the work units by the abrasive areas of the wheels 30.

It may here be noted in passing as desirable 60 that the motor 150 be of reversible type, so as to facilitate reversal of rotation of the associated wheel 140, particularly when grinding soft metal units. Occasional reversal of rotation of the Ferris wheel has been found to deter, minimize 65 and in some cases prevent entirely the tendency otherwise existing for the abrasive discs 30 to become "filled" and their grinding action impaired by gradual surface accumulation of metal particles.

70 Provision for the tilting actuation of wheels 140 and associated elements through a range of at least 90°, as between horizontal and vertical in each direction, is provided for according to one successful design, by securing the Ferris wheel frame rigidly to a rock shaft 160. This

shaft is carried by spaced journal arms or brackets 161, supported on the slideable base 25. Also angularly fixed to shaft 160 are a pair of sector gears 162, which mesh with coacting pinions 163 secured to a lay shaft 164. To the end of the latter shaft is fixed a pinion 165, and the latter meshes with and is rotated by pinion 166. This gear 166 consists, as shown, of the power take-off element of a reduction unit 170, to which is direct-connected a motor 171. In practice, a moderate speed motor, say of 3 H. P. rating, has been found suitable for tilting actuation of the Ferris wheel assembly.

The tilting operation of the Ferris wheel assembly will have been apparent from the foregoing description of its elements, but may be summarized in the notation that motor 171 and reduction gear 170 actuate pinion 166, thence pinion 165 and, through shaft 164, the pinions 163. The latter through their engagement with the sector gears 162 will obviously serve to effect at a reduced rate, the noted tilting action of the Ferris wheel assembly between the position shown at the left hand side of Fig. 1 for loading or unloading the work units, and the vertical position shown at the right hand side of Fig. 2, although it is to be noted that in the latter showing, the wheel has been given an advancing translatory movement to bring it into the grinding field, by means now to be described.

The translatory or shifting movement of each Ferris wheel assembly is cared for by the provision of the slideable base structure 25, operable through a short range of linear movement, on the base elements 20. The latter motion is effected by a hydraulic cylinder 172 (Figs. 1 and 8). The cylinder 172 contains a double face piston and a fluid connection at each of its ends, which may serve alternately for inlet and discharge of oil, for example. The connection of the piston in cylinder 172 may be made directly to a projection (not shown) below the associated base 25. As will later more fully appear in discussing the hydraulic system, admission of fluid to one end and its discharge from the other end of cylinder 172 under valve control will, as now appears obvious, serve to effect a translatory movement of the Ferris wheel assembly toward and into the grinding zone in one direction, and out of the grinding zone to enable further tilting movement of the wheel, pursuant to translatory movement of the wheel in the opposite direction. It will now have appeared as necessary that the wheel 140 be disposed in vertical position incident to the described advancing movement in either direction, and that tilting actuation to horizontal position be effected and possible only when the Ferris wheel assembly is safely beyond the grinder assembly.

Description of grinding method and factors of grinding control

There has been heretofore described in detail a preferred mechanism for attaining a gradual infeed approach of abrasive material and work units. In the example currently described this consists of a very gradual and yet uniform infeed movement of the paired, opposed abrasive discs, where the two thereof are employed. This gradual infeed motion may be regarded as one of the important factors of the present practice and method of grinding.

The second important factor (not necessarily in order of importance) incident to proper con-

trol of rate of abrasion, is the relation between the paths of movement respectively of the work holding portion of the Ferris wheels or their equivalents, and the grinding discs. This factor and a discussion of underlying reasons therefor remain to be presented hereinafter more in detail.

A third important factor in the complete control and best attainment of uniform grinding to close tolerances and in attainment of the self-dressing wheel effect heretofore generally referred to, is a carefully controlled speed of rotation of work holder or Ferris wheel. In the example described this speed is of the order of two to three R. P. M. To be sure, the speed of the work through the grinding field 39 is not entirely independent of the speed of rotation of the grinding wheels, but the noted speed range of the work is predicated upon rotation of the abrasive discs within usual speed ranges; for example, a 48" hollow center wheel, the linear speed of the peripheral portions of a grinder of this diameter is best held within a range of 5600-6000 feet per minute. Considering the Ferris wheel work band as having a speed of seventy feet per minute, there thus results an optimum ratio of linear velocities of the work units and abrasive elements approximating 1 to 80. Obviously some considerable variation from this ratio will still provide excellent results, and a substantially self-dressing wheel, under proper control of the remaining major factors heretofore referred to. It is considered that a usually useful range of ratios between linear speed of work and that of the abrasive particles lies between one to fifty and one to two hundred fifty.

Referring now further to the major factor of control secondly above mentioned, the relation of paths of movement of the work and grinding discs is graphically shown by Fig. 7, being a line drawing, diagrammatic in nature, showing the band of the Ferris wheel in which the work-carrying bushings are located, overlying the circular disc area of a grinder wheel 30. In Fig. 7 the Ferris wheel is again indicated generally at 140 and the work-carrying band at 144 as in preceding figures, with the work holding bushings designated at 145.

It is a distinct preference that each of the discs 30, as noted, be of hollow-center type, and so present an annular grinding face. The circular central area of the disc 30 is closed over with a steel disc indicated diagrammatically at 180, which is kept adjusted so that it lies in or slightly to the rear of the plane of the grinding face of the disc 30. It is felt to be important that the diameter of the hollow center portion of disc 30 and hence of the closure disc 180 therefor, at least equal and preferably slightly exceed the radial width of the work band 144 of the Ferris wheel. By this arrangement, and with the areas of wheels 30 and 140 related and patterned as shown by Fig. 7, it will appear that each of the units of work, in traversing the grinding field 39, is compelled to pass over, without abrasive treatment therein, the area identified with plate 180. It is desirable that the circular median line through work band 144 pass through or extremely close to the projected axis of disc 30.

From the described pattern of work and abrasive paths it will now become apparent that the faces of the work units are first attacked by the more rapidly moving peripheral portions of the disc 30, thence by gradually slower moving abrasive areas so that the grinding rate gradually de-

creases, the speeds of rotation of the wheels 30 and 140 each being assumed as uniform. Following this, metal removal ceases for a time as the work units pass over the plate 180, beyond which grinding is resumed and the rate of grinding again increases until such time as the work units leave the grinding zone in departing from the more rapidly moving peripheral portions of the disc 30. Experience in commercial usage indicates that the described pattern and relation between paths of work and abrasive material, results in a closely uniform removal of metal from each of the batch of several hundred springs or like units in process. A period of commercial experience further teaches that the principles and factors herein described are all of importance in attaining what is an economically important result, namely, the self-dressing feature of protracted wheel operation. Numerous wheels have been successfully operated beyond the stage in which more than one-half their original face material has been worn away, leaving remaining a diminished, yet almost truly planar abrasive surface. Since the costs of wheel replacement and of repeated dressing of wheels are probably the highest components of total grinding costs, the importance of this combination of steps and controls cannot be overestimated.

It may be noted that in further reference to the patterns of work movement and abrasive particle movement, the median of the work path bisects, roughly speaking, the disc area of the wheel. This is more nearly true, the larger the diameter of the Ferris wheel work-carrying band 144 in proportion to the diameter of abrasive disc. In the present example the ratio of these diameters as illustrated is slightly less than two to one; equipment now in process of production closely approximates a two to one ratio of diameter of Ferris wheel band to grinder disc. It is considered that the diameter of work band 144 should be at least one and one-half times that of the abrasive disc, in order usefully to approach the results above expressed in uniformity of grinding of work pieces and in attainment of the self-dressing wheel feature. It may be noted as entirely possible to move the work units unidirectionally and rectangularly or nearly so, in a closed path extending through the work zone. This is in full contemplation as being in keeping with the present method, and as included in the practice of "rotating" the work units through the grinding zone. However, for practical reasons the ultimate in results is closely approximated by rotation of a large-diameter work band through the grinding zone, which work band is within the range of noted ratios to grinder disc face diameters.

Hydraulic control system

Since the major operative units of the assembly have now been described in detail it will appear that the control and control actuation of infeeding mechanism, Ferris wheel transfer, as well as the return actuation of the grinder heads to bring them to initial or starting position, may be effected by a variety or combination of electrical, mechanical, electromechanical, or fluid pressure devices, a number of which, now available to the trade and known in the art, may be adapted to these purposes in the present essential combinations. It is however greatly preferred to employ a hydraulic or other fluid pressure actuated unit to serve the purpose exemplified by the infeed cylinder 64, and its op-

eratively associated adjuncts. The choice of a fluid pressure infeed motor unit results, it is felt, in greater uniformity of infeed motion and one which lends itself to closer regulation of speed and resulting infeed movement of and infeeding pressure upon the grinder heads, than is possible with any other type of mover. Similarly, the selection of hydraulic units for the cylinder 60 provides a number of advantages heretofore noted, not only in a smoother more dependable actuation of the slide base elements but also in a definite cushioning effect above mentioned in the infeed operation. Largely for these reasons, as well as simplicity of structure and relative freedom from excessive service attention, the system selected for description and preferred in usage, is of hydraulic type, preferably an oil filled, uniform-pressure system.

The specific system illustrated includes a number of cylinder and piston actuating assemblies, each of which is or may be of itself of a form old and recognized in the art. The system further includes a number of manual control valves of types especially suited for the present combination, but none of which is, per se, of the design of present applicants, being included herein for completeness of description and complete function of assembly. Each of the several latter units, specifically the control valves and the flow control units, is a product of Vickers, Inc., of Detroit, Michigan, and since the specific valve constructions and the design of the several other flow control units form no part of the present invention, it is regarded as sufficient to refer to them for completeness by catalog or bulletin number designation of their manufacturer hereinafter referred to for brevity as "Vickers." It will be noted, however, that nothing above stated in reference to specific design of flow control or valve units is to be construed as negativing invention in the general combinations within the assembly, including such units.

The hydraulic system considered as a closed circuit flow organization is believed to be readily apparent from the schematic diagram of Fig. 8, in which the single lines connecting the various valves, flow units, pump, and cylinders may consist of conventional seamless metal tubing, say of $\frac{1}{2}$ " outside diameter with connections and fittings of standard type. In Fig. 8 the general arrangement and relative location of the cylinders 60, 172 and 64 approximate the physical arrangement of these parts in the assembly heretofore described.

In the showing of Fig. 8 it will be noted that certain of the fluid leads or connections are indicated in dotted lines. Aside from those thus conventionally shown to indicate portions not normally visible, the remaining dotted lines indicate alternate paths of fluid flow, as effected at times due to the different positions of the valves or flow control units.

By way of general reference to the elements shown by Fig. 8, the hydraulic cylinders 60 are shown in relatively opposed relation and in their preferred paired arrangement, since they are thus located one on each side of the base structure of each of the grinding heads 26. The piston rods of these several cylinders are shown related to the associated intermediate slide base 35. Since, in a double grinder head assembly, the four cylinders 60 are desirably actuated at the same time and through the same range of movement, they are conveniently and as shown, arranged for facultative control through the

valve 190, this valve structure 190 being designated as Vickers Catalog Number C-432-CNS. It is essentially a three-position valve, so arranged as to supply the cylinders 60 to cause, selectively, an approaching movement of the sliding base structures 35, a receding or separating movement of structures 35, and a neutral position in which the pistons of cylinders 60 maintain an intermediate or neutral position. The valve 190 and the remaining portions of the system are kept supplied with a fluid, such as oil under a moderate pressure, through a pumping, storage and accumulator unit, a reservoir or container portion of which is indicated at 191 and may be designated as Vickers Catalog T-6-FC6. Surmounted on the unit 191 is an electric motor 192, preferably direct-connected to an oil pump of centrifugal or rotary type 193, designated as Vickers VC-138-Y208.

Connected into the supply and return leads of the system and pressure-supplied by the unit described, are the two separate control valves, one for each of the transfer cylinders 172. The one of these to the left (Fig. 8) is indicated at 194, and a similar unit 195 which is or may be of identical design, serves to control the companion transfer cylinder at the opposite end of the assembly. Each of these valve units is or may be of three-position type, and so arranged that movement of a valve actuating arm in one direction from neutral moves the transfer cylinder piston, rod and connected Ferris wheel toward one extreme of its path of movement, while manual movement of the handle in an opposite direction, serves to cause a complete shift or translatory movement of the associated Ferris wheel assembly to the opposite extreme of movement. Each of the units 194 and 195 may be supplied as Vickers Catalog Number C-432-CNS.

An infeed cylinder 64 is, similarly to the others described, of double end type in which the fluid under pressure may controllably be supplied to either end of the cylinder, and concurrently discharged from the opposite end. Furthermore, incident to the normal infeeding actuation of piston rod 70 acting upon cam bar 74 and associated elements, the rod 70 will be moved to the right (Figs. 3 and 8) and at a very gradual, yet uniform rate, as heretofore described. This is accomplished by an extremely slow or trickle rate of feed into the left hand end and out of the right hand end of cylinder 64. It has also heretofore been noted as desirable to effect at times a quick return movement of piston rod 70, cam 74 and associated parts. This is accomplished by a reverse direction of flow, but at a considerably faster rate. Accordingly, as the principal control of flow into and from cylinder 64 there is provided a five-position valve assembly designated as Vickers Catalog Number C-485-C, this valve assembly being indicated by reference numeral 196. Two of the five positions of valve 196 are such as, respectively, to cause the piston and cylinder 64 to move rapidly in either direction without specific speed control; two additional control positions of valve 196 cause a flow of fluid to cause movement of rod 70 at a definite, usually low rate of speed in either direction, the speed depending upon the setting of the speed control circuit, while a fifth position of valve 196 causes the piston in cylinder 64 and rod 70, to remain fixed at a predetermined point within their range of travel.

Adjunctive to the infeed control through valve 196, is a flow control unit 197 arranged in the

circuit as shown, and which is referred to as Vickers Catalog Number RC-106-A-1. Also arranged in this portion of the circuit, are a pair of check valve units 200 and 201, each unit of the pair being similar, so that each may be designated as Vickers No. C-800. Each of the units 200-201 is in direct communication with one of a pair of dial valve units 202 and 203. Since these units are or may be identical, they are thought sufficiently designated as Vickers No. F-190-C, the dial valves 202-203 being both in circuit with a control unit 204 which is adequately identified as Vickers No. C-432-EA.

Disposed between the valve 190, and the pump and reservoir unit 191-192-193, is a further flow control unit 205 designated as Vickers No. F-106-D-2. Tubing connections from the latter unit are directed respectively into a pair of similar flow control assemblies 206 and 207 each identified as Vickers No. X-106-D. It may be noted that the several flow control units and valves last referred to by manufacturer's designation, serve, as the dial valve assemblies 202-203, to control rate of flow in the associated branches of the circuits, while others thereof of control as will be apparent, direction and in some cases, rate and extent of flow, being included herein principally for completeness of disclosure of an operative assembly.

Summary of operation

Assuming the machine to have been completely set up with the several stop screws, floating stops and similar elements suitably adjusted to the length and type of work in process, the grinding operation may follow the following suggested course:

One of the fixtures or Ferris wheels 140, with the work units in place therein, is advanced to a position in the grinding field 39. This is accomplished by manually actuating the appropriate hydraulic valve 194 or 195, thus causing the associated transverse cylinder 172 to translate the Ferris wheel to grinding position. The operator 40 then observes the position of hydraulic valve 190 which controls the several cylinders 60 at the sides of each of the grinding heads, so as to ascertain that the position of the pistons is such as to permit pressure to be kept in one end of each 45 thereof, whereby to maintain the intermediate slide base 35 against the selected one of the length-of-work stop screws. This valve position may be referred to as the neutral position, in which the valve 190 is normally maintained at all 50 times except when actuated otherwise for the purpose of changing from one to another length of stop screws, 112 or 113, or for the purpose of displacement to permit attention to, removal of, or servicing of the grinder wheels 30.

The assembly is now conditioned for initiating the grinding operation, and an electric switch in the circuit of motor 150 is now closed, causing the Ferris wheel to rotate, and exposing the work to the abrasive discs 30. It may be advisable, incident to grinding a first batch of work of given 65 finish dimensions, to expose the work to the wheels in successive steps, and intervening such steps, to examine and gauge a few of the work units, until completion of the grinding operation.

At the time of beginning the grinding operation or shortly thereafter, the hydraulic valve 196 is manually shifted to the position causing an infeeding actuation of the piston in infeed cylinder 64. As will now have become apparent, this

causes the piston to move the cam bar 74 from left to right (Fig. 3) very slowly but with regular and uniform motion. In the manner described, the resulting downward vertical motion of cam roller 80 operating through the bellcrank levers, operating bar, and related elements causes the main slide base 36 and all parts thereon, to move in an infeeding direction, i. e. toward the center of the grinding field 39. It will now have become obvious that this same motion is identically although oppositely imparted to the companion grinder head, so as to cause the wheels 30 to approach each other and to approach the center of the grinding field at exactly the same rate.

It will have appeared that stock removal was initiated at the time the first loaded Ferris wheel began its rotation and the valve 196 was first shifted. About this time valve 196 is again manually actuated to a position which first causes the grinder wheels 30 to approach each other and to approach the work at a relatively rapid rate thus causing the load on the motors 31 to build up relatively rapidly. This condition may be accurately ascertained and noted with the aid of the ammeters (not shown) in the motor circuits. As soon as the motors are about fully loaded, the valve 196 is again manually actuated to another of its positions such as to cause the relatively rapid infeed motion to cease, and allowing the speed-controlled hydraulic circuit to function. This circuit, it may be noted, is adjusted by means of one of the dial valves 202 or 203 to such a value that the grinding wheels continue to approach the work without an overload condition on the motors 31. This operating condition is then maintained until such time as the stop elements 96 reach the floating stops 105 and 106, fixing the inner limit of infeed movement of the grinder heads. The loaded Ferris wheel, the work band of which is in the grinding field, continues to rotate for a period during which the wheels 30 are in fixed axial positions at the infeed limit, and until the grinder wheel load (as shown by the ammeters) has dropped down to a predetermined level incident to and following the sparking out period above described.

At this stage of grinding, the Ferris wheel is now temporarily stopped from rotating, a few of the work units removed, gauged for length, and assuming they have attained finish dimensions, the grinding operation has been completed.

If upon measurement of the work units they were found to be of excessive length or incompletely ground, the amount of such excessive length is divided by two and the hand wheel screw 104 is rotated to an extent apportioned to one-half the value of the excessive length. The appropriate extent of hand wheel rotation is noted on a suitable gauge (not shown) in the vicinity of the hand wheel 104. When the work units have been reduced to the predetermined finish size, they are removed from the Ferris wheel as heretofore described.

The valve 196 will now be manually actuated to another position which causes the piston in cylinder 64 to move in a direction opposite that just described. At this stage the hydraulic cylinders 60 act as resilient agencies due to the fluid pressure on their several pistons, and as the low portion of the cam bar 74 reaches the roller 80 the cylinders 60 serve to move the grinding wheels 30 away from each other and away from

the units of work in the Ferris wheel, serving at the same time to maintain the cam follower roller 80 in engagement with the camming face 75 of bar 74.

5 Upon opening the circuit to the Ferris wheel drive motor 150, the Ferris wheel ceases its rotation, following which the associated valve 194 or 195 is operated to cause a retracting transfer movement of the associated cylinder 172. After 10 the Ferris wheel now containing the ground work units is thus brought entirely clear of the grinding field, it is tilted from vertical to horizontal position by closing the circuit to the associated motor 171. The Ferris wheel is now ready for 15 unloading, and when desired, reloading with a further batch of springs or the like, to be ground. The foregoing description has related to the grinding of work units in only one of the work fixtures. Assuming work units of some differing 20 length to be contained in the second Ferris wheel work fixture, the grinding of such different units may be accomplished by first actuating the valve 190 to an extreme position such as to cause the arm 115 on intermediate slide base 35 to move 25 toward the stop screw 117. This effect will be obtained, upon control of the valve 190 as indicated, in each of the opposed grinder units simultaneously. Adjustment for the different length of work pieces in the second Ferris wheel is now 30 made by rotating say through 180°, the turret nut element 110 at each end of the machine so that the positions of the two length-of-work stop screws 112—113 are relatively reversed. The valve 190 is now shifted back to its initial position, causing the intermediate slide base 35 of 35 each grinder head unit, to move back against the newly selected length-of-work stop screw, assuming of course that the latter has been accurately 40 adjusted by threading to a predetermined position suitable for the new batch of work units. The machine is now completely set up to grind the work in the second Ferris wheel, and the latter, after loading, is first brought to vertical position through its motor 171, then translated to 45 a position in the grinding field 39, by manual operation of the associated hydraulic valve such as 195, thus causing the associated transfer cylinder 172 to place the second Ferris wheel in grinding position. The operations heretofore described in reference to the first of the Ferris 50 wheels are now similarly repeated for the second Ferris wheel, except that the opposite dial valve such as 203 is now utilized in establishing the rate of infeed movement of the piston of the 55 cylinder assembly identified with cylinder 64.

It will have been obvious that after some substantial period of grinding, it will be necessary to retract disc 180 somewhat, according to the face wear of the wheel 30. This may be done by 60 any suitable means (not shown) such as clamping elements accessible through small openings in the closure plates 180. Obviously also, occasional minor adjustments must be made incident to wear of the faces of the abrasive discs, since such wear will influence the effective width of 65 the grinding zone 39. Such occasional adjustments may be sufficiently cared for by rotative movement of the elements 111, one of which is provided for each of the grinder assemblies.

70 It will have appeared, as has been determined by commercial usage for several months, that the grinding, work holding and infeeding mechanisms described will serve to attain unusual precision in automatic or semi-automatic grinding equipment, particularly of the types adapted for face-grind-

ing operations, and that the design throughout is such as to attain a novel, useful and economical control of infeed movement, relation of paths of movement of the work and grinding discs, together with a uniform and desirable speed of movement of the work through the grinding field, all in full attainment of the described method or process of grinding and in full realization of the several objects expressly stated as well as those implied.

Although the invention has been described by making specific and detailed reference to a single commercial embodiment of its features, the detail of description is to be understood in a broad rather than in a limiting sense, inasmuch as many changes may be made within the full spirit and intended scope of the claims hereunto appended.

We claim as our invention:

1. In a face grinding assembly, a pair of rotatable spaced grinder wheels arranged in face to face relation, together with means for operating the wheels at uniform rates, a rotary work carrier of substantially greater diameter than either of said grinder wheels, means for rotating the Ferris wheel, holders on a peripheral portion of the Ferris wheel for supporting units of work and rotating said units into and through the grinding field between said grinding wheels along a path such as to subject all abrading portions of the grinding wheels to substantially equal wear, mounting means for the grinding wheels permitting axial movement thereof for infeeding purposes, and infeeding mechanism of a hydro-mechanical type characterized by a slow-rate uniform infeeding motion, the infeeding mechanism including provisions for a trickle feed of pressure fluid during normal infeeding, and the infeeding mechanism being in part common to both of the grinder wheels, whereby to produce an identical low rate movement of the wheels toward the work in the grinding zone therebetween.

2. In a double face grinder assembly for reducing opposite faces of a plurality of work units to be ground, a pair of annular or hollow center grinding wheels arranged face to face but spaced from each other, a rotary work carrier wheel provided with a peripheral annular band of open end compartments adapted to receive the units in work, the carrier wheel being mounted for rotation to bring its work holding portion into and through the grinding field between the two grinding wheels along an arc, the radius of which substantially exceeds the radius of either of the grinder wheels, and with a median of said work holding portion traversing the grinding field close to the axis of the grinding wheels, individual drive motors for each of the grinder wheels and the carrier wheel, together with operative connections between the motors and the respective wheels, the grinder wheel motors and connections being adapted for reverse operation at desired intervals, and infeed power means including a fluid-pressure piston, devices for supplying a trickle feed of fluid under pressure to said piston, motion-reducing means connected to the said infeed power means as parts thereof, and operatively common, at least in part, to both grinder wheels whereby to effect an identical axial, infeed movement thereof at a rate of the order to maintain not more than a light-touch grinding pressure between the wheels and the units in work through the greater part of the grinding period.

3. In a rotary power tool for processing units of metal or the like in work, a base, a work holding member, a tool supporting member, infeeding mechanism for moving one of said members to-

ward the other along said base, and including a fluid-pressure-operated cylinder and piston assembly, a source of fluid pressure connected thereto, a cam element actuated by the piston of said fluid pressure assembly, and characterized by a gradually sloping camming face of a substantial effective length, a follower arranged to be acted upon by said camming face incident to movement of the cam element, and a motion-reducing connection between the follower and said movable member.

4. The combination and arrangement of elements substantially as recited by claim 3, further characterized in that the motion-reducing connection between said follower and said movable member, includes a lever having a long arm and a short arm, said follower being operatively connected to the long arm of the lever, and the short arm thereof being operatively connected to said movable member.

5. In a power grinder for units of metal or the like, a work holding member, a grinder supporting member, a base on which one of said members is linearly movable toward the other, means for effecting an infeed movement of said one member toward the other, and including a power driven, linearly movable cam bar, power means for imparting an extremely slow linear movement to said cam bar, said means acting continuously and uniformly on the cam bar during the period of grinding and normal infeed movement, said cam bar being formed to present a wedge profile of extremely gradually tapering depth, a cam follower having a rolling connection with the cam bar, and a lever serving operatively to connect said follower to said one movable member in motion-reducing relation for effecting infeeding movement thereof toward the other member.

6. In a power grinder for facing units of metal or the like, a work holding member, a grinder supporting member, a base on which one of said members is linearly movable toward the other, means for effecting a linear infeed movement of said one member toward the other, and including a power driven, linearly movable cam bar, means for imparting an extremely slow linear movement to said cam bar, said means acting continuously and uniformly on the cam bar during the period of normal infeed movement, said cam bar being formed to present a wedge profile of extremely gradually tapering depth, a cam follower having a rolling connection with the cam bar, and a lever serving operatively to connect said follower to said one movable member for infeeding movement thereof, said lever having arms of substantially differing length whereby to constitute a motion-reducing connection between the cam bar and said linearly movable member in effecting the infeed motion thereof.

7. A feeding mechanism for effecting an extremely low rate, uniform feeding movement of a power tool toward work in process therewith, the power tool being operatively mounted for movement along a base, a plunger element and means for linearly moving said plunger element at a uniform low rate, a cam bar of elongate form and characterized by a very slightly tapered wedge profile, presenting an elongate camming face, means constraining the cam bar to a rectilinear path of movement, a connection from said plunger to the cam bar, a follower, a rolling element on the follower arranged to be operatively engaged by the camming face of the cam bar, a lever, a fixed pivot for the lever, the lever being characterized by an extremely long arm pivotally connected to the follower, and a short arm opera-

tively connected to the tool supporting member.

8. In a power grinder for face grinding operation on metal units, a grinder head including an abrasive wheel, a base on which the grinder head is axially shiftable for producing an infeed movement of the wheel toward the work units, an infeed-motion-producing mechanism including an elongate plunger and means for actuating the plunger at a substantially low rate along a rectilinear path, an elongate cam bar characterized by a wedge profile and gradually tapering depth from one end of its effective camming portion to the other, a follower yoke through which the cam bar passes, and a lever having a long arm operatively connected to the yoke, and a short arm operatively connected to the grinder head.

9. In a grinder assembly of automatic type, a grinding head including a carriage, a base track upon which the carriage is linearly movable for infeed purposes, a bellcrank lever having a short arm connected to the carriage, and a longer arm, a piston and cylinder assembly, and a source of fluid under pressure connected thereto, an elongate cam operatively connected for slow linear movement by said fluid pressure assembly, a follower connected for a substantially linear movement by said cam, and an operative connection between the follower and the longer arm of said bellcrank lever.

10. In a face grinding assembly, a pair of grinding heads provided with abrasive discs disposed in face to face relation, a base along which the grinder heads are moved toward and from each other for infeed and retracting purposes, infeeding mechanism for the grinding heads, including a piston and cylinder assembly of long stroke proportions, a source of fluid under pressure connected to the cylinder of said assembly, a controllable trickle feed valve adapted to regulate the rate of fluid flow into the piston and cylinder assembly, an elongate cam bar of wedge profile characterized by an extremely gradually sloping camming face, the cam bar being operatively connected to the piston of said assembly, a cam follower, a bellcrank lever for each of said grinding heads, the levers being characterized by relatively short arms connected to the respective grinding heads, and being arranged in relatively opposite or reversed relation, and relatively longer arms of said levers connected to said cam follower in a zone substantially coincident with a median plane of the grinding field between said grinding heads.

11. In a grinding assembly, a base structure, a pair of grinder assemblies oppositely movable on the base, means for simultaneously feeding the grinder assemblies toward and from each other and a unit of work therebetween, paired stops for limiting the relative movement of the grinder assemblies in one direction, means for effecting an identical yet opposite adjusting movement of said stops, including a shaft, means preventing rotation of the stops, and a screw thread connection between the shaft and each of said stops, the threaded connections being oppositely pitched.

12. In a face grinding assembly, grinding means establishing a grinding zone, a pair of holders for the units of work to be ground, one such holder being normally disposed at each side of the grinding zone, individual power means for tilting each work holder to move it between a loading-unloading position and a position close to alignment with the grinding zone, and power means for effecting separate translatory movements of each work holder into and out of position in which the

units of work may traverse the grinding zone, whereby either of the work holders may be moved into the grinding zone while the other holder is in loading-unloading position.

5 13. In a face grinding assembly, a pair of normally spaced grinding heads serving to establish therebetween a grinding zone, a pair of Ferris wheels, each constituting a rotary holder for the units of work to be ground, one Ferris wheel being normally disposed at each side of the grinding zone, means for individually rotating each of the wheels, individual power means for tilting each Ferris wheel between a substantially horizontal work-loading and -unloading position, and a sub-

10 stantially vertical position close to alignment with the grinding zone, a fluid-pressure-actuated piston and cylinder assembly connected to each wheel assembly and adapted for effecting a translatory movement thereof with the wheel in substantially vertical position, to bring it into and out of the work zone between the grinder heads, whereby either of the Ferris wheels may be moved into the grinding zone, while the other Ferris wheel is in a position to receive or discharge units of work.

15 25 14. In combination with a power tool assembly for processing metal units, a rotatable work carrying wheel structure, a plurality of receptacles for the individual work units, arranged on a

30 peripheral part of the wheel structure, and proportioned so that the individual units of work project therefrom, power means for rotating the wheel structure to cause the units to traverse a processing zone, power means for shifting the 35 wheel structure by translatory movement into and out of the processing zone, and power means for tilting the wheel structure about an axis substantially normal to its axis of rotation, and operable so to tilt the wheel structure between a 40 work-receiving and -discharging position, and a position substantially in register with the processing zone.

15 45 15. A Ferris wheel structure for use with power grinding mechanism, including a Ferris wheel constituting a holder for units of work to be ground, means supporting the wheel for rotation about an axis for bringing the work units into a grinding zone, means for rocking the wheel about an axis normal to that of its rotation, whereby to 50 tilt the wheel between a work-receiving position and a position for advancing the units into the grinding zone, said rocking or tilting means including a motor, a reduction gear and tilting connections from the gear to wheel supporting elements.

55 16. In a Ferris wheel structure for use with a power grinder, a Ferris wheel constituting a carrier for units in work to be ground, a frame for the wheel, a power drive for the wheel mounted as a unit on the frame, and power means for tilting the frame and wheel between positions respectively adapted for loading and unloading the wheel, and for enabling the wheel to be advanced to bring the units of work into a grinding zone.

60 17. In a Ferris wheel structure for use with a power grinder, a Ferris wheel constituting a carrier for units in work to be ground, a frame for the wheel, a power drive for the wheel mounted as a unit on the frame, power means for tilting the frame and wheel between positions respectively adapted for loading and unloading the wheel, and for enabling the wheel to be advanced to bring the units of work into a grinding zone, power means for effecting a translatory movement of the Ferris wheel assembly toward and

from the grinding zone, said means including a source of fluid under pressure, a pressure-actuated piston element and associated cylinder element, and a connection between one of said elements and the wheel assembly.

18. In a Ferris wheel assembly for use with a power grinder or the like, a rotatable wheel constituting a carrier for articles in work, means for tilting the wheel between a substantially horizontal position for loading and unloading, and a substantially vertical position wherein the work is adapted to be moved toward, into and from the grinding zone, the wheel being characterized by a narrow peripheral compartmented band, a frame about the wheel, and a plurality of closures, shiftable in a plane substantially parallel to the plane of the wheel, and adapted to aid in retaining the work in the compartmented band when the wheel is in loading position.

19. In a double face grinder assembly, spaced face grinding wheels, a Ferris wheel for carrying units of work into and out of a grinding zone between the grinding wheels, partition means forming pockets in a peripheral portion of the Ferris wheel for containing the units of work, means for rotating the Ferris wheel at a predetermined rate to bring the work through the grinding zone, and means for translating the Ferris wheel into and out of working position with respect to the grinding zone, and means for tilting the Ferris wheel between substantially horizontal and substantially vertical positions at times when the Ferris wheel is displaced from the grinding zone.
